UNITED STATES PATENT OFFICE

MATTHEW McCURRIE, OF SAN FRANCISCO, CALIFORNIA

LETHAL APPARATUS

Application filed November 10, 1930. Serial No. 494,521.

My present invention relates to lethal apparatus of the type used for the extermination of dogs and cats such as are collected at city pounds, and more particularly to a novel arrangement for the control of the gas used in such apparatus, whereby a maximum of safety to the operator is obtained.

An object of my invention is to provide a new and novel apparatus of the above character in which means is provided for preventing the escape of the gas from the chamber during its operation and which will facilitate an easy and rapid disposition of the gas after it has performed its function.

Another object of my invention is to provide a novel arrangement of ventilating conduits for lethal apparatus which can be changed to exhaust gas from an area external of the apparatus or from within the apparatus by the operation of a single valve.

A further object of my invention is to provide in conjunction with apparatus of the above character a novel form of interlocking mechanism between the gas introducing and the ventilating apparatus which will permit the introduction of gas only when the ventilating apparatus is properly operating.

Other objects and advantages of my invention will be in part pointed out and in part evident from the following description taken in connection with the accompanying drawings wherein I have shown by way of illustration and not of limitation a preferred form of my invention.

In the drawings wherein like numerals refer to like parts throughout the several views;

Figure 1 is a side elevation of my improved apparatus with a portion broken away.

Figure 2 is a plan view of the apparatus illustrated in Figure 1.

Figure 3 is an end elevation of the apparatus shown in Figures 1 and 2, and

Figure 4 is a schematic perspective view showing the relative positions of the exhaust conduits and valve therefor.

In the extermination of dogs and cats in a gas chamber of the character contemplated by my invention it is a comparatively safe and simple operation to introduce the gas

into a closed chamber, but the later disposition of this gas after the kill has always been a problem particularly when the lethal chamber is located in a building where it cannot be opened until the gases have been completely exhausted therefrom.

In order to overcome the above difficulties and provide a simple and effective means for exhausting the gas from such a chamber, I show a suitably located exhaust fan having a two-way inlet conduit and a discharge outlet that communicates with the atmosphere, preferably through the roof of a building. The two-way inlet conduit has a valve which serves to properly connect the suction side of the fan with the interior of the chamber when the gas is being exhausted therefrom and with an area adjacent the chamber when the latter is in use.

As a precautionary feature I also show in conjunction with the above conduit valve a suitable interlocking mechanism which will prevent an operation of the valve to close the chamber when the exhaust fan is not operating and also prevent an introduction of gas into the chamber when the valve is not properly set to maintain a suction adjacent the door of the chamber.

In the accompanying drawings 10 designates a rectangular sealed chamber for the reception of a crate or cage 11 in which the animals to be disposed of may be placed. At the front end of the chamber 10 there is provided a door 12 and projecting outwardly from the chamber over the door 12 there is a hood or cowl arrangement 13. At the rear side of the chamber 10 there is also shown a gas container 14 having a suitable connecting pipe 15 through which a gas may be introduced into the chamber 10. The pipe 15 is provided with a valve 16 for controlling the flow of gas from the container 14.

The above described apparatus is all that would be required to carry out the killing of pests where the apparatus can be properly isolated or located in some open space where the attendant can operate same from a safe distance, but when it is desired to operate such an apparatus in a building it is necessary to provide additional means for ex-

hausting the chamber and disposing of the gas in a safe and convenient manner after the kill.

This additional apparatus for disposing of the gas and rendering the apparatus safe, as contemplated by my invention, comprises a suitable exhaust fan 17 that discharges through a conduit 18 leading to the atmosphere, preferably through the roof of a building, and which at its suction side is connected with a two-way or manifold inlet conduit 19. The fan 17 is driven by a suitable electric motor 20 which is controlled by a switch 21 mounted upon the chamber 10. Extending 10 downwardly from the manifold conduit 19 there is a vertical conduit 22 that communicates with the interior of the chamber 10 and a similarly disposed conduit 23 which communicates with the space beneath the hood 13, 15 the connection between the conduit 23 and the space beneath the hood 13 being established by a flaring triangular connection 24 which is perforated at its intake end, as shown 20 at 25 in Figure 3.

25 Communicating with the bottom of the chamber 10 and extending externally thereof to a point in line with the manifold conduit 19, I show a further conduit 26 which communicates with the flaring connection 24 30 through a suitable valve, as will now appear.

Cooperating with the conduits 22, 23 and 35 26, I show a single sliding valve element 27 which serves to open and close the last above conduit and to alternately open and close 40 the conduits 22 and 23. Extending from the sliding valve element 27, I show a link 28 which connects with a bell crank 29 pivotally mounted upon the end of the chamber 10. The bell crank 29 is located adjacent the gas controlling valve 16 and is provided with a 45 downwardly projecting portion 30 which engages an aperture in an operating lever 31 of the valve 16.

The sliding valve element 27 also carries 45 a projection 32 that engages a slot 33 and interlocks it with a switch operating lever 34. The lever 34 is connected at its inner end through a slot 35 with the operating handle of the switch 21 so that when it is pulled out 50 the switch will be in its "on" position and when pushed in the switch will be in its "off" position.

Associated with the slide valve element 27 there is also provided an interlocking mechanism which connects with a suitable door latch 36 for maintaining the door 12 closed 55 when the slide 27 is pulled out to its chamber closing position. This interlocking mechanism may be of any suitable form. In the drawings it is illustrated as comprising a link 37 connecting with the latch 36 and extending up to a lever 38 which is in turn connected through a chain 39 with the slide 27, the chain 39 being passed around a suitably 60 disposed pulley 40. In addition to the latch 65

36 there is also provided a simple snap lock 41.

The bottom of the chamber 10 is shown as raised from the floor and in order to facilitate a rolling of the cage 11 into the chamber I show a suitable incline or ramp 42 which can be lowered by a suitable lever 43 when not in use to permit the closing of the door 12. At the sides of the chamber 10, I also provide oppositely disposed windows 44 and 70 45 through which the operator can observe the 75 conditions within the chamber.

In describing the operation of my device it will be assumed that the gas to be used is obtained in a steel bottle 14 in which the gas 80 is held under pressure. It will be also assumed that the bottle 14 has been properly connected to the chamber 10 by means of the pipe 15 and that the valve 16 is in its closed 85 position.

With the apparatus in this condition the operator can safely open the door 12 of the chamber and roll the cage 11 containing the animals into the chamber. The operator will then move the lever 43 and lower the ramp 90 42 so that the door 12 can be tightly closed. At this point it should be stated that the door 12 is provided with a suitable sealing gasket so that it will close tightly against the 95 escape of gas.

After the chamber has been thus closed, the operator must first pull out the switch operating lever 34 and start the fan 17 before he can open the gas valve 16, however, the normal operation would be to pull out the 100 slide valve 27 and thus by virtue of the interlocking projection 32 he will also operate the switch lever 34. This will close the branch conduits 22 and 26 and open the branch conduit 23, and thus connect the suction side of 105 the fan 17 with the space beneath the hood 13 so as to draw away any gas which might escape through the packing around the door 12.

In pulling out the slide valve 27 the operator will also move the bell crank 29 and 110 withdraw the projecting portion 30 from the operating lever 31 of the valve 16 so that the valve can be opened when desired.

After the valve 16 has been opened a sufficient period of time to fully charge the chamber 10, the operator will then observe conditions within the chamber through the windows 44 or 45 and when he is satisfied that the kill is complete he will push the valve slide 27 inwardly and again lock the valve 16 115 in its closed position. During this last operation it will be understood that the switch lever 34 will remain in its outermost position with the switch 21 "on". This is possible because of the slotted or lost motion 120 connection provided by the projection 32 on the element 27 and the slot 33 on the lever 34. 125

With the sliding valve element 27 in this latter position the branch conduit 23 will be closed and the conduits 22 and 26 will be 130

opened so that the suction side of the fan 17 will be connected directly with the interior of the chamber 10 through the branch conduit 22 and at the same time the conduit 26 will be connected with the flaring conduit 24 and thus a suction will be maintained beneath the hood 13. During this latter operation fresh air will be drawn from beneath the hood 13 through the conduit 26 and into the bottom of the chamber 10 where it will serve to sweep out all of the deadly gases within the chamber and permit its being opened after a very short lapse of time.

After the gas has been removed from the chamber the operator can then safely stop the fan 17 by pushing the switch lever 34 to its innermost or "off" position.

By the above arrangement it will be seen that I have provided a means for readily disposing of deadly gases in a convenient and safe manner and that the arrangement also provides an additional factor of safety in that during the operation of the chamber a continuous suction will be maintained where any leakage of gas is most likely to occur.

In my experiments with various gases I have found that hydrocyanic gas is the most effective for my purpose and while I have illustrated the gas as supplied under pressure from a bottle 14, I desire to have it understood that I may generate the gas in a suitable generator and introduce it through the valve 16 directly into the chamber 10.

While I have, for the sake of clearness and in order to disclose my invention so that the same can be readily understood, described and illustrated specific devices and arrangements, I desire to have it understood that this invention is not limited to the specific means disclosed but may be embodied in other ways that will suggest themselves, in view of this broad disclosure, to persons skilled in the art.

Having thus described my invention, what I claim and desire to secure by Letters Patent is—

1. In apparatus of the character described, the combination of a chamber having a door at one end, means for introducing a gas into said chamber, a hood extending outwardly from said chamber over said door, a suction fan having two inlet conduits, one connecting with the interior of said chamber and the other connecting with the space beneath said hood, a valve for alternately opening one or the other of said inlet conduits of said fan, and an interlocking mechanism between said valve and said gas introducing means, whereby the gas cannot be introduced into said chamber until the conduit leading from the chamber is closed and the conduit leading to said hood is opened.

2. In apparatus of the character described, the combination of a chamber having a door

at one end, means for introducing a gas into said chamber, a hood extending outwardly from said chamber over said door, a motor driven suction fan having two inlet conduits, one connecting with the interior of said chamber and the other connecting with the space beneath said hood, a switch for controlling the motor of said fan, a valve for alternately closing one or the other of the inlet conduits of said fan, and an interlocking mechanism between said valve and said switch, whereby the conduit between said fan and said chamber cannot be closed until said fan motor is operating.

3. In apparatus of the character described, the combination of a chamber having a door at one end, apparatus for introducing a gas into said chamber, a motor driven suction fan for exhausting the gas from said chamber, a switch for controlling the motor of said fan, a conduit leading from said fan to the interior of said chamber, a valve for opening and closing said conduit, and an interlocking mechanism between said valve and said switch and gas introducing apparatus for preventing an introduction of gas into the chamber when said fan is not operating and the conduit valve is open.

4. In apparatus of the character described, the combination of a chamber having a door at one end, apparatus for introducing a gas into said chamber, a suction fan for exhausting the gas from said chamber, a conduit leading from said fan to the interior of said chamber, a valve for opening and closing said conduit, and an interlocking mechanism between said valve and said gas introducing apparatus for preventing an introduction of gas into the chamber when said conduit valve is open.

5. In apparatus of the character described, a chamber having a door at one end, means for introducing a gas into said chamber, a hood extending outwardly from said chamber over said door, a motor driven suction fan having an inlet conduit connecting with the space beneath said hood, a switch for controlling the motor of said fan, a valve for opening and closing the inlet conduit of said fan, and an interlocking mechanism between said valve and said switch, whereby said fan motor cannot be started until the valve in said conduit is opened.

6. A system of exhaust conduits for lethal apparatus of the character described, comprising a suction fan having a discharge outlet leading to the atmosphere, an inlet conduit leading to said fan, said inlet conduit having two branch conduits, one leading into the interior of the chamber and the other leading to a point beneath a hood projecting over the door of said chamber, a further conduit connecting said last branch conduit with the bottom of the chamber, and a single valve cooperating with said last conduit and said

branch conduits for permitting a suction to be established beneath said hood when in one position and permit a similar suction to be maintained from beneath said hood and an exhaust of the chamber when in another position.

7. In apparatus of the character described, the combination of a chamber having a door at one end, apparatus for introducing a gas into said chamber, a motor driven suction fan for exhausting the gas from said chamber, a lock for maintaining said door closed when said chamber contains gas, a conduit leading from the atmosphere and through said fan to the interior of said chamber, a valve for opening and closing said conduit, and an interlocking mechanism between said valve and said lock for preventing the opening of the door in the end of the chamber when said conduit valve is not open.

8. In apparatus of the character described, the combination of a lethal chamber, a door at one end of said chamber, a ventilating hood extending outwardly over said door, a suction fan for exhausting the space beneath said hood, means for introducing a lethal gas into said chamber, and an interlocking mechanism between said fan and said gas introducing means which prevents the introduction of gas into said chamber when said fan is not operating to exhaust the space beneath said hood.

9. In apparatus of the character described, the combination of a lethal chamber, a door at one end of said chamber, a lock for maintaining said door closed, means for introducing a lethal gas into said chamber, and an interlocking mechanism between said door lock and said gas introducing means which prevents the introduction of gas into said chamber when said lock is in its door releasing position.
